UNITED STATES PATENT OFFICE.

ADOLPHE ANTOINE FRANCOIS MARIUS SEIGLE, OF PARIS, FRANCE.

APPARATUS FOR COOLING HYDROCARBON GASES AND VAPORS AT HIGH TEMPERATURES.

Application filed August 11, 1921, Serial No. 491,382, and in France July 25, 1918.

This invention relates to an apparatus for obtaining the more or less relative cooling of the vapors and gases which are discharged directly or indirectly at a high temperature from furnaces, gas retorts or like apparatus employed for distillation, pyrogenation or thermo-chemical reactions such for instance as are employed in the mineral oil industry, the said cooling being however carried out 10 with a very considerable absorption of heat and is also regulated in a sufficiently easy manner.

This cooling operation, which may be termed primary cooling, usually precedes 15 the operations of complementary fractional condensation and final cooling, these being carried out conjointly with the former by the use of known cooling or temperature exchanging devices.

20 This invention will be understood from the following description, given solely by way of example, of a special application to the thermo-chemical treatment of the more or less liquid or tarry residues of the distillation of schistous sandstone, lignite, peat, crude oil, rich coal, and the like. For this application, the primary cooling apparatus is preferably constructed according to the device shown in the accompanying drawings 25 wherein:

Fig. 1 is a vertical section of the whole apparatus. Figs. 2 and 3 are horizontal sections on the lines 2—2 and 3—3, Fig. 1.

The cooling apparatus comprises an outer 30 receptacle of sheet iron or steel A and a second receptacle secured in a more or less permanent manner at the middle part of the former. This inner receptacle is constituted chiefly of three cylindrical or conical portions which as far as possible are made in a single piece of cast iron, steel or the like, or in other cases constructed by boiler work of sheet iron, copper or other metal and solidly secured together in order to afford a 35 sufficient heat-conducting capacity for the assemblage formed by the parts above mentioned.

These three parts comprise the following members:

40 The cylinder B having at the base thereof a circular flange which is bolted to the bottom of the receptacle A.

The conical member B' connecting the 45 said cylinder B with the upper conical member C which is closed at the bottom by a

disk J having therein a set of concentric apertures adjacent the circumference, Fig. 1.

The cylindrical chamber A' which constitutes to some extent the central annex of the outer receptacle A by the use of the two 50 horizontal connecting tubes y and z, Figs. 1 and 3.

The said cylindrical chamber A' is closed at the top by a metal cover s which is permanently secured in place by four screws co-operating with four suitable lugs s' and which serves as a support for a disc r (Fig. 1). The lower aperture of the cylinder B is closed by the bottom of the receptacle A and by a disc r' of cast iron, steel or bronze 55 of considerable thickness and having cast therewith the central tube E. Upon the said thick disc r' are screwed two cocks F, F', one of these being provided with the tube F'' which extends up into the cylinder B, 60 Figs. 1 and 2.

In the annular space between the central chamber A' and the inner wall of the cone C are disposed successively the three metal plates x which rest upon suitable supports 65 x', Fig. 1. Two of the said plates have radially extending portions cut out to provide for disposing the said plates below the connecting tube y, Figs. 1 and 3. The three plates x have formed therein concentric sets 70

of apertures K, the apertures of each plate being staggered relative to the aperture in the adjacent plates. The staggered arrangement of the apertures causes a tortuous flow 75 of fluid through the apparatus as indicated by the arrows, Fig. 1. The disc r extends inside the above mentioned annular space and acts itself as a baffle with respect to the aperture in the upper plate x. The operation of mounting the plates x and the disc r, is 80

carried out at the same time as the filling 85 of the spaces between the three plates and the said disc with iron turnings or shavings, granulated iron or like material m which is suitable for the thermo-chemical treatment of the heavy hydrocarbons above mentioned. At the end of these simultaneous operations the cover D is hermetically secured to the cone C. The last measure 90 consists in providing for the good condition and tightness of the piping which is used with the following various admission or discharge apertures: E for the inlet of the 95 hydrocarbon vapors, D' for the discharge of the non-condensed vapors, cock F provided 100

105

110

with the tube F" for observing the filling of the cylinder B with the products of condensation, cock F' for the discharge of the latter, cock G for the inlet of the boiling water, and cock H for the discharge of the steam.

Having now described the method of constructing the said apparatus and of disposing the same in working order, this apparatus being given solely by way of example, the operation will be set forth as follows:

To simplify the question, the annular space in the receptacle A, the two tubes y, z and the central cylinder A', Figs. 1 and 3, may be considered without inconvenience as being almost entirely filled with water which is already heated to the desired boiling point, this operation being readily observed by the pressure gauge I, Fig. 1. A cock or valve, not shown, is then opened to connect the tube E for instance with the discharge tube of a retort wherein is carried out the distillation of a more or less pyrogenic character of a certain quantity of fuel oil or astatki, at a high temperature, say 450° C. The hydrocarbon vapors thus introduced through the tube E will flow into the portions B, B' of the apparatus, expanding at the same time, and will proceed through the sets of baffle holes as shown by the arrows, Fig. 1, and throughout the whole mass of iron turnings, granulated iron or like material which as above stated are caused to fill up the entire annular space between the inner cylinder A' and the conical member C.

It should however be remembered that the said cooling and expansion apparatus is brought either by means of the outer surfaces of the cylinder B and the cones B' and C or by the inner surface of the cylinder A' almost entirely in direct contact with water which has already reached the boiling point. If on the other hand it is considered that the vaporization of the water will absorb in a practically instantaneous manner at least ten times the quantity of heat absorbed by the same water more or less slowly when rising from 10° to 60°, as occurs in a considerable number of the known cooling apparatus, it will be readily observed that when passing through the various internal parts of the expansion cooling apparatus herein described, the more or less pyrogenic and gasified vapors will be incompletely but very quickly cooled, and will expand and become decomposed or depolymerized to a greater or less degree, thereby setting free a considerable portion of their heat, this latter being thereupon absorbed by the instantaneous vaporization of a corresponding quantity of water which had been already brought to the boiling point.

The supplying of the chambers A A' with already-heated water is easily and economically carried out, especially by the use of

water which has been already used for cooling the final cooling or fractional condensation devices which are traversed by the vapors and gases discharged from the primary cooling condenser. But as in this first operation the water in question has not been raised to a high temperature, it may be employed to good advantage as a spray for condensing the steam discharged from the chambers A A' through the valve or cock H, whereby this water will be finally brought to a sufficiently high temperature. An economical supplementary heating of the feed water for the chambers A A' may also be obtained by the use of the heat of the gases of combustion of the furnace pertaining to the distillation retort above mentioned.

According to the pressure maintained in the chambers A A', the temperature will rise to a greater or less degree within the condenser. In usual practice, this pressure is more or less above atmospheric pressure, but should it become necessary to reduce the said temperature, this may be carried out by reducing the pressure of vaporization of the water in the chambers A A', and if required this may be reduced considerably below atmospheric pressure. To carry this out, it will suffice to draw off the vapor more or less rapidly through the passage H, by means of a pump or like device.

Moreover it is possible also to regulate the temperature of the boiling water by adding a certain and variable quantity of chloride of calcium for instance.

Having now described my invention, what I claim as new and desire to secure by Letters Patent is:

1. In an apparatus for cooling hydrocarbon gases and vapors the combination of a vertical receptacle, a central chamber extending axially through said receptacle, means for admitting the supply of the hydrocarbon gases and vapors to be treated to the space within said receptacle and around said central chamber, a jacket surrounding said receptacle, means for supplying cooling fluid to said central chamber and to the space between said jacket and said receptacle and an outlet at the upper part of said receptacle for the noncondensed gases and vapors.

2. In an apparatus for cooling hydrocarbon gases and vapors, the combination of a vertical receptacle, means for admitting the supply of the hydrocarbon gases and vapors to be treated to the lower end of said receptacle, a central chamber closed at both ends within said receptacle and extending axially through the upper part thereof, a jacket surrounding said receptacle, means for supplying cooling fluid to the space between said jacket and said receptacle, means affording communication between said central chamber and said space, horizontal cross

- plates supported within said receptacle and around said central chamber, apertures in said plates, the apertures of one plate being so disposed with respect to the apertures in the adjacent plates as to provide a tortuous flow of the gases and vapors through said receptacle and an outlet at the upper part of said receptacle for the non-condensed gases or vapors.
- 10 3. In an apparatus for cooling hydrocarbon gases and vapors the combination of a vertical receptacle, means for admitting the supply of the hydrocarbon gases and vapors to be treated to the lower end of said receptacle, a central chamber closed at both ends within said receptacle and extending axially through the upper part thereof, a jacket surrounding said receptacle, means for supplying to the space between said jacket and said receptacle water under predetermined pressure and at a temperature substantially equal to the boiling temperature corresponding to
- 15 said pressure, means affording communication between said central chamber and said space, horizontal cross plates supported within said receptacle and around said central chamber, apertures in said plates, the apertures of one plate being so disposed with respect to the apertures of the adjacent plates as to provide a tortuous flow of the gases and vapors through said receptacle, an outlet at the upper part of said receptacle for the noncondensed gases or vapors and means for evacuating the steam generated within said space.
- 20 4. In the combination as claimed in claim 3 the further feature residing in that suitable materials are disposed on-said horizontal plates for the chemical treatment of said hydrocarbon gases and vapors.

In testimony whereof I have signed my name to this specification.

ADOLPHE ANTOINE FRANCOIS MARIUS SEIGLE.
